United States Patent

Des. 237,010
Patented Sept. 30, 1975

237,010

COMBINED RIBBON AND CARTRIDGE THEREFOR
Keith L. Gnutzman, Alameda, and Ernest P. Hess, Castro
Valley, Calif., assignors to Xerox Corporation, Stam-
ford, Conn.

Filed Dec. 3, 1973, Ser. No. 420,989

Term of patent 14 years

Int. Cl. D18—01

U.S. Cl. D64—11 A

FIG. 1

FIG. 2

FIG. 3

FIG. 4

FIG. 5

FIG. 6

FIG. 7

FIG. 1 is a perspective view of a combined ribbon and cartridge therefor showing our new design.

FIG. 2 is a front elevational view thereof.

FIG. 3 is a right side elevation view thereof.

FIG. 4 is a bottom plan view thereof.

FIG. 5 is a top plan view thereof.

FIG. 6 is a left side elevation view thereof.

FIG. 7 is a rear elevational view thereof.

We claim:

The ornamental design for a combined ribbon and cartridge therefor, as shown.
